(57) **CLAIM**

The ornamental design for a probe thermometer, as shown.

DESCRIPTION

FIG. 1 is a perspective view of the probe thermometer showing our new design;

FIG. 2 is a right side elevation view of the probe thermometer shown in FIG. 1, the left side elevation view being a mirror image thereof;

FIG. 3 is a front elevation view of the probe thermometer of FIG. 1;

FIG. 4 is a top plan view of the probe thermometer shown in FIG. 1;

FIG. 5 is a bottom plan view of the probe thermometer shown in FIG. 1;

FIG. 6 is a back plan view of the probe thermometer shown in FIG. 1;

FIG. 7 is a perspective view of an alternate embodiment of the invention in which a portion of the probe of FIG. 1 is uncovered;

FIG. 8 is a perspective view of an alternate embodiment of the invention in which a portion of the probe of FIG. 1 is uncovered;

FIG. 9 is a right side elevation view of the probe thermometer of FIG. 7, with the left side elevation view being a mirror image thereof;

FIG. 10 is a front elevation view of the probe thermometer of FIG. 7;

FIG. 11 is a top plan view of the probe thermometer of FIG. 7; and,

FIG. 12 is a back elevation of the probe thermometer of FIG. 7.
